Inventor

Alfred William Flint

Peg B. Singer, Atty.

UNITED STATES PATENT OFFICE.

ALFRED WILLIAM FLINT, OF LONDON, ENGLAND.

DEVICE FOR REMOVING CLOSURES FROM BOTTLES.

Application filed October 11, 1924. Serial No. 743,064.

To all whom it may concern:

Be it known that I, ALFRED WILLIAM FLINT, a subject of the King of Great Britain, residing at 2 Harewood Place, Oxford Street, London, W. 1, England, have invented new and useful Improvements in or Relating to Devices for Removing Closures from Bottles, of which the following is a specification.

- 10 This invention relates to devices for removing closures from bottles and has for its object to provide a new or improved device capable of use as a corkscrew or as a crown stopper opener.
- 15 According to the invention a combination tool is provided comprising two elements either of which can constitute or form part of the operating handle for the other according to whether the device is to be used 20 as a corkscrew or for removing a crown stopper. The corkscrew may be adapted to embrace the shank of the crown stopper removing tool which may also be passed through an aperture in the corkscrew shank 25 in each case to form a handle whilst in another form of the invention the corkscrew may be pivotally mounted on the handle of the crown stopper removing tool.

Reference will now be made to the accompanying drawings which illustrate by way of example constructions according to the invention and in which:

Figure 1 is an elevation of a device consisting of two completely detachable elements,

Figure 2 is an elevation similar to Figure 1 but showing an alternative form of crown stopper removing tool,

Figure 3 illustrates the method of using the device shown in Figure 1 or 2 as a corkscrew.

Referring first to Figure 1 a crown stopper removing tool *a* is formed at one end with a pair of prongs *b* and *c* adapted to engage respectively above and below the crown of a stopper, the prong *b* being so shaped as to exert a positive grip beneath the crown. The shank portion *d* of this

element is of such diameter that it can be pushed through the helical coils *e* of the 50 corkscrew element which grip it frictionally to a sufficient extent to enable the shank *f* of the corkscrew to act as a handle, when the device is to be used for removing a 55 stopper, the combined length of the two elements thus assembled forming a tool of sufficient length to enable the requisite amount of leverage to be exerted to remove a stopper easily. The engagement between the coils *e* of the corkscrew and the shank *d* 60 is sufficiently tight to prevent all except intentional disengagement so that the device can most conveniently be carried so engaged without risk of one element becoming misplaced. The device illustrated 65 in Figure 2 is in all respects similar to that of Figure 1 with the exception of the crown stopper removing tool which has a single prong *g* having an inwardly projecting tooth *h*, this form being suited to stoppers of shapes that could not be engaged by the double prong shown in Figure 1.

The manner of using either of the devices above described as a corkscrew is shown in Figure 3. In each case the corkscrew shank *f* is formed with a transverse aperture *i* through which the shank *d* of the crown stopper tool can be passed, the shank *d* being so proportioned that substantially only half its length can pass 70 through the aperture *i* so that the crown stopper opener with its shank forms a handle for the corkscrew.

I claim:

A device for removing closures from bottles, comprising a crowned cap remover having a shank, and a cork screw having a shank provided with an opening to receive the shank of the cap remover to enable the cap remover to be employed as a handle, 85 the convolutions of the cork screw being of such radius as to enable the shank of the cap remover to be arranged therein.

In witness whereof I affix my signature.

ALFRED WILLIAM FLINT.
